(57) **CLAIM**

The ornamental design for a sealing and connection cap, as shown and described.

DESCRIPTION

FIG. 1 is a perspective view of a sealing and connection cap which may be used as part of a soil sensor housing;

FIG. 2 is another perspective view thereof;

FIG. 3 is a top view thereof;

FIG. 4 is a front view thereof;

FIG. 5 is a side view thereof;

FIG. 6 is a rear view thereof; and,

FIG. 7 is an underside view thereof.

The broken lines are shown for illustrative purposes only and form no part of the claimed invention.
